LLP(57) **CLAIM**

The ornamental design for a panel display plate, as shown and described.

DESCRIPTION

FIG. 1 is a front perspective view of the panel display plate;
FIG. 2 is a front elevation view thereof;
FIG. 3 is a rear elevation view thereof;
FIG. 4 is a right side elevation view thereof;
FIG. 5 is a left side elevation view thereof;
FIG. 6 is a top view thereof;
FIG. 7 is a bottom view thereof;
FIG. 8 is a front perspective view of a panel display plate in
an environment of use;
FIG. 9 is a front perspective view of a panel display plate in
an alternate environment of use; and,
FIG. 10 is a front perspective view of a panel display plate in
another alternate environment of use.
The broken lines illustrate environmental features and form
no part of the claimed design.

1 Claim, 8 Drawing Sheets(56)
